Primary Examiner — Antoine D Davis*(74) Attorney, Agent, or Firm* — Kory D. Christensen; Stoel Rives LLP(57) **CLAIM**

The ornamental design for a telemetry monitor, as shown and described.

DESCRIPTION

FIG. 1 is a front perspective of an embodiment of a telemetry monitor showing our new design;

FIG. 2 is a rear perspective view thereof;

FIG. 3 is a top plan view thereof;

FIG. 4 is a bottom plan view thereof;

FIG. 5 is a front elevation view thereof;

FIG. 6 is a right side elevation view thereof;

FIG. 7 is a left side elevation view thereof; and,

FIG. 8 is a rear elevation view thereof.

The broken lines immediately adjacent the shaded areas represent the bounds of the claimed design, while all other broken lines are directed to environment and are for illustrative purposes only; the broken lines form no part of the claimed design.
